CLAIM

The ornamental design for a combined housing and handle assembly for a line trimmer, as shown and described.

DESCRIPTION

FIG. 1 is a perspective view of a combined housing and handle assembly for a line trimmer, showing my new design, the broken line showing the cutting head is for illustrative purposes only, and forms no part of the claimed design;

FIG. 2 is an enlarged left side elevational view thereof;
FIG. 3 is an enlarged right side elevational view thereof;

FIG. 4 is an enlarged top plan view thereof;

FIG. 5 is an enlarged bottom plan view thereof;

FIG. 6 is an enlarged back end elevational view thereof;
and,

FIG. 7 is an enlarged front end elevational view thereof.
